US00D921037S

(12) **United States Design Patent** (10) **Patent No.:** **US D921,037 S**
(45) **Date of Patent:** **** Jun. 1, 2021**

(54) **DISPLAY SCREEN OR PORTION THEREOF
WITH ICON**

(71) Applicant: **23andMe, Inc.**, Mountain View, CA (US)

(72) Inventors: **Tracy Keim**, Altadena, CA (US); **Sooyun Choi**, Mountain View, CA (US); **Sampo Aleksi Jalasto**, Mountain View, CA (US); **Joel Parsons**, Helsinki (FI); **Jesse Jouni Sakari Maula**, Menlo Park, CA (US)

(73) Assignee: **23andMe, Inc.**, Sunnyvale, CA (US)

(**) Term: **15 Years**

(21) Appl. No.: **29/680,749**

(22) Filed: **Feb. 19, 2019**

Related U.S. Application Data

(62) Division of application No. 29/597,377, filed on Mar. 16, 2017, now abandoned, which is a division of application No. 29/543,031, filed on Oct. 20, 2015, now Pat. No. Des. 785,672.

(57) **CLAIM**

The ornamental design for a display screen or portion thereof with icon, as shown and described.

DESCRIPTION

The patent file contains at least one drawing executed in color. Copies of this patent with a color drawing will be provided by the Office upon request and payment of the necessary fee.

FIG. 1 is a front view of a display screen or portion thereof with icon showing the claimed design;

FIG. 2 is a second embodiment thereof; and,

FIG. 3 is a third embodiment thereof.

The broken lines in the figures show a display screen or portion thereof, and form no part of the claimed design. All broken lines within the display screen or portion thereof illustrate portions of the icons and icon sets for illustrative purposes only and form no part of the claimed design.

**1 Claim, 1 Drawing Sheet
(1 of 1 Drawing Sheet(s) Filed in Color)**
